DEVICE FOR RECLAIMING SAND.

1,079,979.

Specification of Letters Patent.

Patented Dec. 2, 1913.

Application filed March 27, 1912. Serial No. 686,544.

To all whom it may concern:

Be it known that we, WENDELL C. FLETCHER and LAWRENCE E. BROWN, citizens of the United States, and residents of the city of St. Louis, State of Missouri, and city of Somerset, county of Pulaski, and State of Kentucky, respectively, have invented certain new and useful Improvements in Devices for Reclaiming Sand, of which the following is a specification.

Our invention relates to the art of metal founding and has particular reference to a device for reclaiming sand after being used in the production of castings in sand molds.

It is well known that in the formation of molds in which metal castings are made, sand is used to a large extent and this sand to be suitable must have particular characteristics, that is, a certain proportion must be sharp and to this end dust must be eliminated therefrom. It has been customary to entirely discard the sand after being once used, and inasmuch as such sand was easily procured the cost was slight; furthermore to separate the sharp sand from the dust entailed some expense. However, in large establishments where extensive founding is carried on the item of sand 30 becomes considerable and for this reason many forms of apparatus have been devised whereby the sand after being once used may be treated, to the end that the dust and fine particles may be removed and the sharp sand returned to the foundry for reuse. However, the original cost as well as the cost of operation of many of these reclaiming devices has made such processes so expensive that it was equally economical 40 to procure new sand.

It is the principal object of our invention therefore to provide apparatus which shall efficiently act upon used sand whereby the fine particles may be removed leaving the sharp sand for reuse.

It is a further object to produce such a machine which shall be simple and inexpensive in construction and economical in operation.

The principle of the present machine is that of allowing the sand to pass over a series of baffles whereby the particles are separated and each thereof exposed to a blast of air, the lighter particles being held

in suspension and carried with the air, the heavier particles falling by gravity into a proper receptacle.

Our invention will be more readily understood by reference to the accompanying drawings, wherein the figure is a vertical section through my novel separating device.

Referring more particularly to the drawings it will be seen that sand is supplied to a hopper 12, from which hopper it is admitted into the separating device 13. From the bottom of the separating device cleaned sand is elevated by a chain conveyor 14, to a chute 15, which may direct the sand into a proper receptacle by means of which it is returned to the foundry for reuse.

It will be understood that the parts heretofore described are mounted on suitable supports and such supports will not be described in detail.

The sand as it comes from the foundry is conveyed into the hopper 12 entering at the point 19, striking the V-shaped deflector 20 and a portion thereof passing on each side thereof. The bottom wall of the hopper 12 is contracted at two points and openings normally closed by gates 21, permit the egress of sand as desired into the separator 13. This separator is constructed preferably with imperforate side walls and has a hopper shaped bottom wall 22. Extending transversely of the side walls of the separator 13 are a plurality of perforated deflectors 23. These deflectors, as shown in Fig. 2, are mounted in pairs, all of the pairs of deflectors having substantially the same vertical center line, that is, a vertical line drawn through the center of the uppermost deflector would pass through or near to the center line of any of the deflectors in that row. These deflectors are mounted at an angle of substantially 45 degrees, and at their lower outer ends are provided with a large number of relatively small perforations, the number of perforations increasing with the size of the baffle until the lowermost baffles 24 are reached, these having only a few perforations at their outer ends, their inner ends being joined at 25. In the side walls we provide air inlet and exhaust openings 26, 27, respectively, air under pressure being supplied through the conduit 26, then passing under the baffle 24, being di-

vided as it passes upwardly, a portion thereof entering between each baffle, finally passing out through the exhaust opening 27.

It will be noted that the baffles are mounted at different distances from each other, both vertically and horizontally, that is, that the larger baffles are mounted closer together than the smaller thereof. The result of this is that the area being decreased the speed or velocity of the air will be increased, the velocity decreasing as the area becomes greater. Thus it will be seen that the sand entering the separator from the hopper 12, impinges very slightly, the first baffle then falls on the perforated portion of the second baffle; from there onto the perforated portion of the third baffle and so on, the sand being broken up and separated as it passes downward, giving the blast of air access to each particle. At the lowest point it will be seen that the velocity of the air is greatest and this is the point where the final test between the velocity of the air and the relative weight of the particles of sand takes place. Of course, the blast of air might be made strong enough to carry all the sand out the waste or exhaust opening 27, therefore the blast must be regulated whereby the separation of the waste sand to the proper point takes place. The lighter particles will be separated and carried out at relatively higher points in the separator, the finest dust being carried away immediately as it escapes from the hopper 12. The sand which has sufficient mass to withstand the blast of air, passes over the ends of the baffles 24, thence into the hopper 22, where it is restrained by a gate 28. A chute 29 leading from the hopper 22, directs the cleaned sand into conveyer 14, by means of which it is elevated and dumped into the chute 15, and from thence into a car or other receptacle.

It will be seen that the mechanism herein described is very simple of construction; that the parts may be easily assembled in any foundry or manufacturing establishment and that the only expense in operation will be the power needed to operate the conveyers and to provide the blast of air. It has been demonstrated in practice that a reclaiming device such as herein described will reclaim at least ten tons of sand per hour, the cost thereof being inconsiderable.

Many modifications may be made in the exact construction herein shown and described, all without departing from the spirit of our invention.

We claim:

1. In a device of the class described, the combination of a casing having an air inlet and an outlet, means for delivering sand to be cleaned to said casing by gravity action, and a series of baffles of unequal areas disposed transversely of said casing, the baffles of greatest area being disposed beneath those of less area, the outer edges of said baffles being provided with a plurality of perforations, substantially as described.

2. In a device of the class described, the combination of a casing having an air inlet and an outlet, means for delivering sand to be cleaned to said casing by gravity action, and a series of baffles of unequal areas disposed transversely of said casing, said baffles being separated by unequal distances, the baffles of greatest area and of least separation being disposed beneath those of less area and greater separation, substantially as described.

3. In a device of the class described, the combination of a casing having an air inlet and an outlet, means for delivering sand to be cleaned to said casing by gravity action, and a series of baffles of unequal areas disposed transversely of said casing, said baffles being separated by unequal distances, the baffles of greatest area and of least separation being disposed beneath those of less area and greater separation, the outer edges of said baffles being provided with a plurality of perforations, substantially as described.

4. In a device of the class described, the combination of a casing having an air inlet and an outlet, means for delivering sand to be cleaned to said casing by gravity action, and a series of baffles of unequal areas disposed transversely of said casing, said baffles being separated by unequal distances, the baffles of greatest area and of least separation being disposed beneath those of less area and greater separation, the outer edges of said baffles being provided with a plurality of perforations, the inner line of perforations in adjacent baffles being substantially in a vertical line, substantially as described.
